TAPE CASSETTE BOX

Robert S. Wallace, 2706 S. Robertson Blvd.,
Los Angeles, Calif. 90034

Filed Apr. 10, 1970, Ser. No. 22,364

Term of patent 14 years

Int. Cl. D3—01

U.S. Cl. D87—1

FIG. 1 is a front perspective view of a tape cassette box showing my new design in partly open condition;

FIG. 2 is a rear perspective view thereof showing the top and side opposite that shown in FIG. 1;

FIG. 3 is a rear bottom perspective view thereof in closed condition; and

FIG. 4 is a side elevation thereof in closed condition.

I claim:

The ornamental design for a tape cassette box, substantially as shown and described.
